[57] ABSTRACT

A mechanical watch movement comprising a minute-wheel and pinion, a cannon pinion with a toothng which meshes with that of the minute-wheel and an hour-wheel coaxial with the cannon-pinon and cooperating with the minute-wheel pinion, wherein the minute-wheel pinion is thicker than the minute-wheel, the minute-wheel pinion further comprises teeth each having for at least a portion of its thickness a lateral face in the form of an arc of a cylinder coaxial with the minute-wheel pinion whereas some of the teeth each have a point extending beyond the lateral face, said lateral face thus being thinner than the minute-wheel pinion, the minute-wheel is driven onto the lateral faces and the outside diameter of the toothng of the hour-wheel is such that only the points cooperate with the hour-wheel toothng.

FIG. 1

FIG. 2

MECHANICAL WATCH MOVEMENT

This invention relates to a mechanical watch movement comprising a minute-wheel and pinion, a cannon-pinion with a toothing which meshes with that of the minute-wheel, and an hour-wheel coaxial with the cannon-pinion and cooperating with the minute-wheel pinion.

In conventional mechanical watch movements, the cannon-pinion bears a minute-hand at the end of its pipe, while the hour-wheel itself bears an hour-hand. The pipe of the cannon-pinion and that of the hour-wheel pass through a central opening in the dial, the latter being placed directly against the outer face of the base-plate. In order for the cannon-pinion to rotate at the rate of one revolution per hour, and the hour-wheel at the rate of one revolution every 12 hours, the reduction ratios between the cannon-pinion and the minute-wheel on the one hand, and between the cannon-pinion and the minute-wheel on the one hand, and between the minute-wheel pinion and the hour-wheel on the other hand, must be such that their product equals 12. In certain known movements of this type, the minute-wheel and pinion constitute the driving members of the dial-train; and when the minute-wheel and pinion are directly coupled to the barrel-drum, the movement must be designed in such a way that the barrel-drum rotates at a speed determined by the said reduction ratios.

Watch movements are also known in which the cannon-pinion and the hour-wheel carry discs entirely covered by the dial. These discs bear minute- and hour-indications which appear in an aperture in the dial. In movements of this type, the hour-wheel is generally driven by jumps of one-twelfth of a revolution per hour, whereas the cannon-pinion is driven in continuous motion.

The minute-wheel and pinion of mechanical watch movements often comprise a pinion which is thicker than the wheel, the latter being driven onto a cylindrical bearing surface produced by lathe-turning on a portion of the thickness of the pinion. Thus the teeth of the pinion are eliminated, and its hub is reduced in diameter for as much of its thickness as is necessary for driving on the minute-wheel. When the minute-wheel and pinion are intended to drive a jumping hour-wheel, on the other hand, different designs are used, with the minute-wheel and pinion comprising a two- or three-tooth star in the center.

It is the object of the present invention to provide for more efficient mass-production of watch movements. A more particular object is to enable the production of both movements with hour- and minute-hands and movements equipped with hour- and minute-indicating discs starting from the same caliber and using the same elements to the greatest extent possible.

To this end, in the mechanical watch movement according to the present invention, the minute-wheel pinion is thicker than the minute-wheel, and the minute-wheel is driven onto the teeth of the minute-wheel pinion.

Two embodiments of the invention will now be described by way of example with reference to the accompanying drawings, in which:

FIG. 1 is a partial axial section of the first embodiment,

FIG. 2 is a partial top plan view on a larger scale of the minute-wheel and pinion of the movement shown in FIG. 1,

FIG. 3 is a partial section analogous to that of FIG. 1, showing the second embodiment, and

FIG. 4 is a top plan view of the hour-wheel and the minute-wheel and pinion in the second embodiment.

The movement partially illustrated in FIG. 1 is of simplified construction. It comprises a frame consisting of 10 a base-plate 1, a wheel-train bridge 2, and a balance cock (not shown), these various elements being fastened to one another by pillars, such as pillar 3, riveted to the base-plate 1 and to one of the bridges. A main-spring is fitted in a barrel-drum 4 situated between the 15 bridge 2 and the base-plate 1 and mounted on a detachable arbor 5 which is axially fastened by a bolt 6 making it axially integral with the hub of the drum 4. Extending between the bridge 2 and the drum 4 is a ratchet-wheel 7 integral with a sleeve 8 which is situated inside the drum 4 and serves to hook the inner end of the mainspring. The arbor 5 pivots in an opening in the bridge 2 and a corresponding opening in the base-plate 1. It projects into a recess 9 in the outer face of the base-plate 1 and is provided with a square 10 at the end 25 of it. Engaged on the square 10 is a non-circular central opening of a minute-wheel-and-pinion assembly 11 which is fitted in the recess 9 and which rotates with the barrel-drum 4. The minute-wheel 12 of this assembly 11 meshes with a cannon-pinion 13, while its minute- 30 wheel pinion 14 meshes with an hour-wheel 15 coaxial with the cannon-pinion 13. The cannon-pinion 13 is mounted on an inner pipe 16 integral with the base-plate 1. The cannon-pinion pipe proper and the pipe of the hour-wheel 15 pass through a central opening in a 35 dial (not shown) and bear a minute-hand and an hour-hand, respectively, at their ends. The movement described further comprises a fourth-wheel-and-second-pinion assembly 17, the arbor of which is engaged in the inner pipe 16; this assembly 17 forms part of the 40 wheel-train connecting the barrel-drum 4 to an escape- ment (not shown). It will be noted that the ratchet- wheel 7 is blocked by a click 18 actuated by a spring (not shown) and pivoting on a cylindrical bearing surface of the pillar 3.

45 Since the arbor 5 rotates with the barrel 4 and drives the minute-wheel-and-pinion assembly 11, the gear ratios between the wheel 12 and the cannon-pinion 13 on the one hand, and between the pinion 14 and the wheel 15 on the other hand, must be such that the cannon- 50 pinion 13 rotates at the rate of one revolution per hour, while the wheel 15 rotates at the rate of one revolution every twelve hours. Moreover, for reasons which will become apparent later on, the speed of rotation selected for the barrel 4 is one revolution every 4 hours. 55 As a result, the gear-ratio between the wheel 12 and the cannon-pinion 13 is 4:1, while the reduction-ratio between the pinion 14 and the wheel 15 is 1:3.

The structural details of the minute-wheel-and- 60 pinion assembly 11 are shown in FIG. 2. The pinion 14 has a peripheral toothng made up of 12 teeth 19, the tracing of which is visible in FIG. 2. This tracing is that of a standard toothng, the teeth of which are cut off at approximately half their height by lateral faces 20 in the form of portions of a cylindrical surface coaxial with the pinion 14. Thus all the teeth 19 are cut off at the same height, and the lateral faces 20 define an 65 imaginary cylindrical surface which constitutes the en-

velope of the pinion 14. The wheel 12 has a circular central opening 21, the diameter of which is the same as that of the imaginary cylindrical surface defined by the lateral faces 20. The wheel 12 is driven directly onto the teeth 19 and extends between the middle of the thickness of the pinion 14 and one of its frontal faces, so that the truncated teeth 19 are free for approximately half the thickness of the pinion 14. The hour-wheel 15 has a 36-tooth toothing 22 with a normal tracing and a module equal to that of the toothing 19. These standard-profile teeth mesh with the teeth 19 even though the latter are truncated at mid-height, as may be seen in FIG. 2, so that the pinion described drives the wheel 15, which rotates continuously, completing one revolution every 12 hours.

The assembly 11 is completely sunk into the recess 9. On the other hand, the wheel 12 is engaged with a setting-wheel (not shown) which cooperates with the other members of the setting mechanism and which likewise pivots on the outer face of the base-plate 1.

The minute-wheel and pinion may be dismantled very easily, and after they have been removed, it is possible to extract the arbor 5 by grasping it by a projecting head 23, which enables the barrel to be taken out laterally.

The second embodiment, shown in FIGS. 3 and 4, is based on an identical caliber to that of FIG. 1. Thus FIG. 3 again shows the base-plate 1 with its recess 9 and the barrel-arbor 5. These elements, as well as the bridge 2, the barrel 4, and the elements of the wheel-train, are also identical. The barrel 4 and the arbor 5 likewise rotate at a speed of one revolution every four hours.

A minute-wheel-and-pinion assembly 24 is composed here of a toothed disc, identical to that of the first embodiment and accordingly designated by the reference numeral 12, and a pinion 25 of a slightly different design. This pinion 25 is of the same thickness as the pinion 14, and its central opening is likewise of the same size and shape. However, its toothing differs in that it comprises eight teeth 26 identical to the teeth 19, i.e., laterally limited by lateral faces 20 in the form of cylindrical portions coaxial with the pinion, and four teeth 27 which, as may be seen in FIG. 3, have a lateral face 28, in the form of a portion of a cylindrical surface of the same diameter as the faces 20, for about half of their thickness. However, as these faces 28 take up only half the thickness of the pinion 25, the four teeth 27, each having a point 27a, project beyond the imaginary cylindrical surface limited by the faces 20 and 28. These four points 27a have a normal tooth profile. They are positioned at 90° from one another around the axis of the pinion 25.

Whereas the wheel 12 driven onto the faces 20 and 28 of the pinion 25 meshes with a cannon-pinion 33, the toothing of which is identical to that of the cannon-pinion 13, the points 27a of the pinion 25 cooperate with an hour-wheel 29 which is designed differently from wheel 15. As will be seen in FIG. 4, there is at the periphery of the wheel 29 a toothing made up of 12 triangular teeth 30. These teeth 30 cooperate with a jumper 31 mounted in the recess 9 of the base-plate 1. This jumper 31 normally holds the wheel 29 in a fixed position. The diameter of the circle defined by the apexes of the teeth 30 is such that the wheel 29 can rotate freely without coming into contact with the teeth 26 of the pinion 25 but is caught by the points 27a of

the teeth 27. On the other hand, the dimensions are such that each point 27a can displace the wheel 29 by an angle sufficient for the apex 32 of the point of the jumper 31 to pass over the apex of one of the teeth 30. Starting from this position, the resiliency of the jumper 31 advances the wheel 29 to the position shown by the dash-line in FIG. 4, where the two flanks of the jumper 31 are simultaneously in contact with two of the teeth 30. Via its points 27a, therefore, the pinion 25 advances the hour-wheel 29 by jumps of one-twelfth of a revolution every time the pinion 25 rotates 90°.

In this embodiment, the pipes (not shown) of the cannon-pinion 33 and of the wheel 29 will be shorter than in the first embodiment, and they carry a minute-disc and an hour-disc (not shown), respectively. These discs will be situated between the base-plate 1 and the dial (not shown), and the minute- and hour-indications printed along the peripheries of the discs will appear in an aperture in the dial. In this embodiment, the fourth-wheel-and-second-pinion assembly 17 will not comprise any pivot intended to receive the seconds-hand, and the dial need not have a central opening.

As a variation of the embodiment according to FIGS. 3 and 4, the teeth 27 might also be full for their entire thickness. In that case, the central opening of the disc 12 will be blanked with notches corresponding to the teeth 27 so that this disc can be driven onto the pinion.

Whereas the pinion 14 can be made either by blanking from a circular disc or by milling a standard tooth-ing at the periphery of the disc, then lathe-turning the teeth to the diameter defined by the faces 20, the pinion 25 will preferably be made by milling the teeth 26 and 27, then lathe-turning the lateral faces 28 and the lateral faces 20 to a thickness corresponding to that of the faces 28, the piece in which the teeth 26 and 27 are milled being initially blanked so that the teeth 26 are truncated as shown in FIG. 4.

It has been found that minute-wheels and pinions such as those described above, and particularly such as the assembly 24, of simplified construction, drive the cannon-pinion and the hour-wheel under conditions corresponding to conventional conditions. In particular, despite the fact that the teeth of the pinion 14 are truncated for approximately half their height, an hour-wheel with a conventional toothing, such as wheel 15, meshes perfectly with them. In the embodiment having a jumping hour-wheel, since the distance between the axes of the barrel and the cannon-pinion is the same as in the caliber with continuous drive of the wheel 15, the star 29 will have a slightly smaller diameter than the wheel 15. Moreover, it will have only one-third as many teeth.

What is claimed is:

1. A mechanical watch movement comprising:
a minute-wheel pinion having a plurality of teeth each having a lateral face portion in the form of a cylindrical arc coaxial with said minute-wheel pinion, at least some of said teeth having a further substantially pointed portion which extends from and beyond said arcuate face portion;
a toothed minute-wheel having a thickness which is less than the thickness of said minute-wheel pinion and fixed to said arcuate lateral face portions of said minute-wheel pinion;
a cannon-pinion having teeth which mesh with said toothed minute-wheel; and

a toothed hour-wheel coaxial with said cannon-pinion and having an outside diameter such that only said pointed portions of said minute-wheel pinion engage said toothed hour-wheel.

2. A watch movement in accordance with claim 1, wherein the hour-wheel is normally held in a fixed position by a jumper acting upon its toothing, and said pointed portions are so disposed that the hour-wheel is driven in jumps of one unit of circular pitch of its toothing by each point of the minute-wheel pinion.

3. A watch movement in accordance with claim 1, wherein said minute-wheel is coupled to a barrel-drum.

4. A watch movement in accordance with claim 3, wherein said minute-wheel is situated on the outer face of a baseplate of the movement.

5. A watch movement in accordance with claim 4, wherein said minute-wheel is fitted in a recess in said baseplate.
